UNITED STATES PATENT OFFICE.

JACOB MANDEL, OF NEW YORK, N. Y.

FUEL-SAVER.

1,168,951.

Specification of Letters Patent. Patented Jan. 18, 1916.

Application filed April 8, 1915. Serial No. 19,937.

To all whom it may concern:

Be it known that I, JACOB MANDEL, a citizen of the United States, and a resident of the city of New York, borough of Manhattan, in the county and State of New York, have invented a new and improved Fuel-Saver, of which the following is a full, clear, and exact description.

This invention relates to stoves and furnaces, and has particular reference to attachments for fuel burners for the purpose of causing a more uniform and complete combustion of the fuel than usually takes place.

15 Among the objects of the invention, therefore, is to provide a sort of drum construction to take the place of a section or joint of stove pipe or furnace flue, the same being provided with means automatically operated 20 by the draft created upwardly in the pipe or flue, to cause a certain amount of downward pressure or draft of fresh air which, combining with the gases tending to escape, will create a condition of uniform draft and 25 nearly perfect and complete combustion.

Another object of the invention is to establish a certain definite ratio between the upward draft through the pipe or flue to the 30 downward pressure created thereby, thus increasing the downward pressure in proportion 35 to the upward draft.

The foregoing and other objects of the invention will hereinafter be more fully described and claimed and illustrated in the 40 drawings forming a part of this specification in which like characters of reference indicate corresponding parts in all the views, and in which—

Figure 1 is a vertical sectional view of a 45 preferred embodiment of the invention; and Fig. 2 is a horizontal view, partly in section, on the line 2—2 of Fig. 1, arrows on both figures indicating the supposed direction of movement of the currents and fan.

The several parts of this device may be 50 made of any suitable materials, and the relative sizes and proportions of the same, as well as the general design of the mechanism, may be varied to a considerable extent without departing from the spirit of the invention hereinafter more fully described and 55 specifically claimed.

Referring more particularly to the drawings I show at 10 a drum or casing comprising in the main two spaced concentric cylindrical shells 11 and 12 of any suitable length

and the diameter of the inner shell 11 corresponding preferably to a standard diameter of stove pipe or furnace flue for which the drum structure is designed, the device 60 taking the place of one length or joint of such pipe or flue. The shells 11 and 12 are or may be of substantially the same length, but the inner shell projects sufficiently above the outer one to receive the next pipe joint 65 thereupon in the usual manner of connecting stove pipe joints. The space between the shells is bridged at the upper end of the shell 12 by an annular collar 13 having holes 13' therethrough of suitable size; otherwise 70 the space between the upper end of the shell 12 and the shell 11 is closed. The collar, therefore, serves as a connector and brace between the two shells.

The lower ends of the shells 11 and 12 are 75 connected rigidly by a frusto-conical rim 14 flaring downwardly. This rim has a series of perforations 14' therethrough, preferably considerably smaller in area than the holes 13'.

At the lower end of the drum is formed a 80 substantially cylindrical collar 15 of a size adapted to fit over the next lower pipe or flue joint. This collar is connected to the lower end of the shell 12 by an imperforate 85 upwardly flaring frusto-conical rim 16 making a strong rigid support for the several shells and connecting parts and forming within the rims 14 and 16 a sort of combustion or mixing chamber for the upwardly 90 disposed gases and downwardly directed currents of air.

At any suitable place within the shell 11 and journaled upon an axis parallel to or coinciding with the axis of the shell 11 is a 95 fan 17 having a plurality of blades radially arranged but each inclined or formed in such a manner as to be acted upon by the normal upward draft in the pipe or flue through the shell 11. The axis 18 of the 100 fan is shown journaled in bearings 19 and 20 in a rigid bracing device 21 secured within the shell 11 and transversely thereof. The bracing device preferably comprises two substantially parallel bars having feet 105 or ends turned at an angle to the main portions thereof and secured snugly and rigidly against the inner surface of the shell 11 on opposite sides of a circumferential slot formed entirely around the shell 11 in the 110 plane of the axes of the wings or blades of the fan and through which slot the ribs 22

constituting the axes of the fan blades extend into the space between the two shells. Upon these outer ends of the ribs 22 are secured auxiliary fan blades 23, the axes of which are in alinement with the respective main fan wings but inclined in the opposite direction. The upward or outward currents of air or products of combustion passing through the shell 11 acting upon the main fan blades cause a rotation of the fan in the direction indicated in Fig. 2. The auxiliary fan blades 23 being carried rigidly by the ribs 22 of the fan are hence caused to sweep around in the space between the two shells 15 with a velocity proportional with the velocity of movement of the main fan wings. Since the auxiliary wings are so inclined as to direct the air downwardly within the space between the two shells, fresh air is drawn freely downwardly through the holes 13' and jetted forcibly downwardly through the perforations 14' toward the axis of the device. Since the velocity of the fan is dependent upon the force or velocity of the upward or outward drafts or currents, it follows that with the increase of the draft due to varying conditions of combustion in the stove or furnace or outside weather conditions, the force of the auxiliary fan blades 23 acting downwardly upon the fresh air will be proportionally increased.

It is well known that in the usual furnace conditions, large quantities of valuable fuel are wasted in the form of unconsumed gas

or smoke delivered from the flue or chimney. 35 I am aware furthermore that previous attempts have been made to counteract this tendency to loss of fuel by the introduction of fresh air by various means into the flue. I believe, however, that I am the first to 40 cause the introduction and downward forcing of such fresh air by means of devices whose effect is variable directly in proportion to the outward draft.

I claim:

In a fuel saver, the combination of a shell through which an outward draft is adapted to pass, a shell surrounding the first mentioned shell and spaced therefrom, a rotary device journaled within the inner shell and movable in a plane perpendicular to the axis of said shell, said rotary device including a series of wings inclined so as to be acted upon in a certain direction by the force of the draft through the inner shell, auxiliary wings connected to the main wings and sweeping around the inner shell within the space between the two shells, the auxiliary wings being inclined in a direction to cause a current of air through said space between the shells in a direction opposite to the direction of draft and to the space within the inner shell, and means to support the two shells.

JACOB MANDEL.
